UNITED STATES PATENT OFFICE.

JAMES SHARKEY, OF BROOKLYN, NEW YORK.

DESIGN FOR CEMETERY FENCES AND GATES.

Specification forming part of Design No. 6,765, dated July 8, 1873; application filed May 5, 1873.

To all whom it may concern:

Be it known that we, JAMES SHARKEY, of Brooklyn, in the county of Kings and State of New York, have invented a new and original Design for Entrances and Fence for Cemetery Inclosures, of which the following is a specification:

The nature of my design is fully represented in the accompanying photographic illustration, to which reference is made.

A is the entrance consisting of steps C, curved side buttresses B, gate D, and gate-

pillars E E. F are the fence-posts, and G the rails, forming together a design for the front, and inclosing fence of a cemetery-lot, substantially as represented.

I claim as my invention—

1. The above design, as represented and specified.
2. The design of the gate D, as shown.

JAMES SHARKEY.
